UNITED STATES PATENT OFFICE.

BOB CATCHINGS, OF BIRMINGHAM, ALABAMA.

WATER-CLOSET BOWL.

1,155,885.

Specification of Letters Patent.

Patented Oct. 5, 1915.

Application filed May 26, 1914. Serial No. 841,111.

To all whom it may concern:

Be it known that I, BOB CATCHINGS, a citizen of the United States of America, residing at Birmingham, in the county of Jefferson and State of Alabama, have invented new and useful Improvements in Water-Closet Bowls, of which the following is a specification.

This invention relates to improvements in 10 water-closet bowls and has particular application to a rest for such bowls.

In carrying out the present invention, it is my purpose to provide a rest for bowls of the class described whereby the use of the 15 common wooden and metal seats will be eliminated and which will be clean and sanitary in construction.

It is also my purpose to provide a rest for bowls of the type set forth whereby the 20 limbs of the person using the bowl will be conveniently and comfortably supported.

With the above and other objects in view, the invention consists in the construction, combination and arrangements of parts 25 hereinafter set forth in and falling within the scope of the claim.

In the accompanying drawing; Figure 1 is a top plan view of a bowl constructed in accordance with the present invention. Fig. 30 2 is a view in side elevation thereof. Fig. 3 is a similar view showing a modified form of the invention.

Referring now to the drawing in detail and particularly to the form of my invention illustrated in Figs. 1 and 2, 1 designates 35 a bowl of any suitable or preferred construction. In accordance with my present invention, this bowl has the upper edge or rim 2 thereof formed after the fashion of a saddle and is provided with relatively high front and back pieces 3 and 4.

Formed integral with the bowl at the front portion thereof adjacent to the rim 2 and projecting outwardly therefrom are foot rests 5 disposed at opposite sides of the longitudinal center line of the bowl and adapted to support the weight of the user of the bowl. The upper edge of the bowl contiguous the front 3 is relatively narrow as clearly shown in Fig. 1 in order to facilitate 50 the use of the bowl.

In the form of my invention illustrated in Fig. 3, I have illustrated a construction whereby the valve of the flush tank is opened automatically in the use of the bowl and in this instance a push button 7 is carried by the rests 5 and connected through suitable mechanism with the valve. Thus, in the use of the bowl, the push button 7 is depressed thereby opening the valve to flush the bowl. 60

I claim:

A water closet bowl having the upper edge thereof formed after the fashion of a saddle and having relatively high back and front pieces, and foot rests formed integral 65 with the outer surface of said bowl, each of said rests being provided with a flat horizontal portion to receive the ball of the foot and a second flat portion arranged at a lower elevation for receiving the heel of the user in combination with the flushing mechanism having a portion thereof slidably mounted in the heel receiving portion of one of the 70 rests.

In testimony whereof I affix my signature 75 in presence of two witnesses.

BOB CATCHINGS.
